UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

CORE-OVEN.

SPECIFICATION forming part of Letters Patent No. 662,303, dated November 20, 1900.

Application filed January 8, 1900. Serial No. 722. (No model.)

To all whom it may concern.

Be it known that I, THOMAS I. RANKIN, a citizen of the United States, residing in Philadelphia, Pennsylvania, have invented certain 5 Improvements in Core-Ovens, of which the following is a specification.

My invention relates to certain improvements in ovens for baking cores used in making castings.

10 One object of my invention is to so construct the oven that it will evenly and thoroughly bake the cores; and a further object of the invention is to make the oven continuous, so that the core-carriages can enter the oven at 15 one end and after the cores are baked the carriages can be removed at the opposite end of the oven, as fully described hereinafter.

In the accompanying drawings, Figure 1 is a longitudinal sectional view of my improved 20 core-oven. Fig. 2 is a sectional plan view. Fig. 3 is an end view. Fig. 4 is a section on the line 4 4, Fig. 1. Fig. 5 is an enlarged section on the line 5 5, Fig. 1. Fig. 6 is an enlarged sectional view of the front end of the 25 furnace; and Fig. 7 is a sectional view on the line 7 7, Fig. 6.

A is the oven, which is of sufficient width and height to accommodate the core-cars F. (Shown in outline in Fig. 7.) Extending 30 through the oven is a track the rails a a of which are in the form of I-beams and are supported on suitable foundations. The rails extend beyond each end of the oven, and cross-rails a' are provided at the front of the furnace, 35 and cross-rails a' are provided at the rear of the furnace. At a point where these rails cross the oven-rails a a I provide a turn-table a³, so that the core-cars can be shifted from the cross-rails to the oven-rails, and when the 40 cores are baked they can be shifted from the oven-rails to the other cross-rails. The cross-rails connect with rails throughout the foundry.

Directly under the front of the oven is a fire-chamber B, communicating through a flue b with the oven A. The flue enters the oven near the forward end and between the rails.

B' is the ash-pit, and b' is the grate.

Situated under the center of the oven is a 50 return-flue D, communicating with the oven

through a passage d at the rear of the furnace and communicating near the forward end of the furnace with the stack D'. A damper d', consisting of a plate movable horizontally and constructed to give varying degrees 55 of opening to the return-flue, is provided at the rear of the furnace at the point in the floor where said flue communicates with the oven. This damper can be operated without opening the oven. I make the portion between the oven and the return-flue of light material, preferably sheet-iron, as shown in Fig. 5, so that the heat of the products of combustion passing through the return-flue will tend to heat the floor of the oven. The sheet-iron floor c is preferably curved and rests upon the base-flange of the I-beams, as shown in Fig. 5.

E E' are doors hinged to the oven structure and arranged so as to open wide to allow the 70 core-cars F to enter or leave the oven. The core-cars F are mounted on suitable wheels f f and carry the core-plates f', on which the cores are placed. These plates, as well as the ears, are perforated, so as to allow the products 75 of combustion to bake all portions of the core.

The core-cars are coupled together by any suitable means and are traversed through the furnace by an endless driving-chain i, which passes around the driving-wheel I at one end 80 of the furnace and a wheel I' at the opposite end of the furnace. Either one or both of these wheels may be the driving-wheel, and I preferably gear the shaft of the driving-wheel to a hand-shaft by a gear and pinion, 85 Fig. 7, so that the wheel can be more readily turned. The chain is connected to the several cars by links i', so that the cars can be drawn through the oven without opening the doors, except to insert or remove a car and without 90 the operator entering the oven.

I preferably arrange the floors or the rails on which the cars travel on a slight incline from the forward end to the rear, so that the cars can be more readily traversed through 95 the oven. In fact, the incline is such that the chain to which the cars are attached is under tension at all times and the operator simply releases the chain to allow the cars to move forward by their own weight. It 100

may be necessary in some instances to hold the cars, which can be done by locking the hand-wheel.

By placing the fire-chamber in such position that it will communicate with the forward end of the oven I am enabled to place the car as it enters the oven immediately over the flue *b*, which is the hottest point in the oven. Thus a crust is immediately baked upon the entire surface of the core, preventing shrinkage to any great extent and holding the core intact during the further movement of the core-car through the furnace.

As the core-cars are moved forward they are subjected to sufficient heat to thoroughly bake each of the cores, and when the core-cars are removed from the furnace the cores are browned evenly, and I have found that each core has been thoroughly baked. The return-flue adds materially to the heat of the oven.

While I have shown cars for supporting the cores, the cores may be supported on slides or other carriers which can be traversed through the oven.

I claim as my invention—

The combination in a core-oven, of a long chamber, a track extending therethrough, doors at each end of the chamber, a furnace directly under the forward end of the chamber, and communicating directly with the chamber between the rails of the track through a flue, a return-flue directly under the center of the chamber, between the rails of the track, and communicating with the rear of the chamber, and with a stack situated near the forward end of the chamber, and a curved partition between the return-flue and the chamber being thin so that the floor of the chamber will be heated by the return products of combustion, substantially as described.

In testimony whereof I have signed my name to this specification in the presence of two subscribing witnesses.

THOMAS I. RANKIN.
